UNITED STATES PATENT OFFICE

JAMES N. VILLANO, OF SYRACUSE, NEW YORK

PRESS

Application filed June 17, 1932. Serial No. 617,727.

This invention relates to an improved fruit and vegetable press for family use in expressing juices and liquids from various kinds of fruits and vegetables, such for example, as grapes, berries, oranges, grapefruit, lemons, and other juice containing materials from which it is desired to recover the juices separately from the solids.

Presses of this character are generally used only for short intervals during each year or during the ripening season of the fruits and vegetables which necessitates the storing of the press during the remaining or greater portion of the year, and one of the objects is to provide a knock-down press in which the various elements or units may be easily and quickly taken apart and thoroughly cleansed throughout their entire surfaces and then stored in relatively small compact space until the time comes for reuse when the parts may be quickly reassembled without special tools.

It is well-known that the beds of presses of this kind against which the materials are pressed are subjected to more severe strains and wear and, therefore, require more frequent repairs or replacements than other parts.

This is particularly true of beds which are made of wood or equivalent fibrous material which, in addition to their susceptibility to wear and disintegration after a relatively short period of use, tend to absorb and retain considerable portions of the expressed juices and particularly their flavors, so that after the press has been used to express the juices of one kind of fruit and then reused for expressing the juices of an entirely different kind of fruit or vegetable, the latter would be more or less tainted or impregnated with the flavors of the previously expressed juices which may have been absorbed by the wood or fibre.

One of the principal objects of the present invention is to provide a concrete bed which may be thoroughly cleansed from previous juices and flavors so that when reused for expressing the juices of other fruits or vegetables the bed will not be appreciably

impregnated with the flavors of the previously expressed juices.

Another object is to construct the receptacle for receiving the material pressed in the form of a cylinder composed of a multiplicity of similar parallel upright slats bound together by one or more split bands locked together by a removable key or rod in such manner that when the locking key is removed the entire series of slats with the band or bands attached thereto may be unfolded in a substantially flat plane so as to permit all parts of the slats and bands to be thoroughly cleansed from foreign matter.

Another object is to construct and assemble the various parts of the press in such manner that an ordinary screw jack may be used as the means for compressing the material in the receptacle through the medium of a suitable pressure plate or follower.

Other objects and uses relating to specific parts of the apparatus will be brought out in the following description.

In the drawing:—

Figures 1 and 2 are side elevations of my improved press at right angles to each other, portions of the bed in Figure 1 being shown in section, the supporting legs for the bed in both views, being partly broken away.

Figure 3 is an enlarged horizontal sectional view taken in the plane of line 3—3, Figure 2.

Figure 4 is an enlarged detail vertical sectional view taken in the plane of line 4—4, Figure 2, showing more particularly the manner of attaching one of the legs to the concrete bed.

As illustrated, this press comprises a horizontal bed —1— of concrete, such as sand, cement and fine gravel proportioned in such manner as to produce a closely knit homogeneous aggregate with a minimum porosity so as to preclude as far as possible its saturation with the expressed juices and thereby to reduce the liability of retention of the flavors of said juices for any appreciable period of time, the object being to enable the press to be used for expressing

the juices of widely different fruits or vegetable without liability of transmission of the flavors of one juice to another from the bed.

5 This concrete bed is preferably polygonal but symmetrical in top plan and is provided in its upper side with a substantially annular trough —2— extending entirely around the vertical axis of the bed and preferably inclined downwardly from one side toward its diametrically opposite side where it is provided with an outlet —3—, as shown more clearly in Figures 2 and 3.

10 This trough is arranged some distance within the marginal edges of the bed except at the outlet —3— where the bed is projected outwardly to form a nozzle —4— through which the outlet is continued, to allow the liquid to be precipitated therefrom into an underlying receptacle, not shown.

15 The concrete bed —1— is preferably supported upon a plurality of, in this instance four, legs —5— arranged uniform distances apart about the vertical axis of the bed in downwardly diverging angles, the upper ends of said legs being threaded and engaged with internally threaded metal sockets —6— which are imbedded in the concrete during the process of moulding so 20 as to become permanent parts thereof, the object being to allow the legs to be removed by unscrewing the same from the sockets when it is desired to disassemble the various units of the press.

25 30 35 The portion of the upper side of the bed within the trough —2— is preferably circular and disposed in a horizontal plane slightly below that of the upper surface of the marginal edges of the bed and also slightly above the bottom of the groove —2— for receiving and supporting a receptacle —7— for the material to be pressed.

The legs —5— are preferably formed of wrought iron pipe or equivalent material 40 capable of being threaded and screwed into the sockets —6— to firmly support the bed —1— in a horizontal plane.

45 50 55 The bed —1— is provided with a pair of wrought iron or equivalent reinforcing rods or bars —8— imbedded therein some distance below the upper surface thereof during the process of moulding said bed and are preferably arranged in the same horizontal plane and in parallel relation equal distances from and at opposite sides of the vertical axis of the bed and at right angles to the longitudinal center of the nozzle —4—.

60 65 These reinforcing rods extend outwardly equal distances beyond opposite sides of the bed —1— to form trunnions —8'— for receiving and supporting a pair of upright frames or tie rods —9— which extend upwardly from the bed some distance above the upper end of the receptacle —7— for

receiving and supporting at their upper ends a cross beam —10—, shown more clearly in Figures 1 and 2.

70 These frames —9— are arranged in parallel spaced relation vertically at diametrically opposite sides of the bed —1— and each frame is preferably formed from a single rod of wrought iron or equivalent material bent into the form of an inverted U and having its opposite legs as —9'— diverging downwardly from the upper cross bar —9'—, the lower end of each of the arms —9'— being returned upwardly upon itself to form an eye —10'— which is loosely fitted over and upon its corresponding trunnion —8'—, the upper ends of the return bends being fastened to the corresponding arm by wire clamps —11— or equivalent fastening means, as shown in Figures 1 and 2.

75 80 85 The concrete bed —1— is also provided with a pair of diametrically opposite anchor bolts —12— imbedded therein during the process of moulding and having their outer ends extended some distance beyond and midway between the lower ends of the upright frames —9— for receiving a clamping plate —13— and nuts —14—.

90 95 100 105 The clamping plates —13— extend horizontally equal distances from their respective bolts —12— across the outer faces of the adjacent portions of the frames —9— with their lower edges resting upon the upper faces of the trunnions —8'— where they are clamped in position by the tightening of the nuts —14— to hold the lower ends of the frames —9— against accidental displacement from their respective trunnions —8'—, the object of engaging the opposite ends of the plates —13— with the upper faces of the corresponding trunnions —8'— being to prevent turning of said plate when tightening or loosening the adjacent nuts —14—.

110 115 120 125 As previously stated, the receptacle —7— is cylindrical and is arranged with its lower end loosely resting upon the upper surface of the central depressed portion of the bed —1— just at the inside of the trough —2— and is preferably composed of a series of upright slats —7'— arranged in uniformly spaced relation circumferentially around the vertical axis of the bed and preferably bound together by a plurality of, in this instance two, split metal bands —15—, the latter being arranged in vertically spaced parallel relation between the lower and upper ends of the slats.

130 These slats are permanently secured by bolts —16— or equivalent fastening means to the inner faces of the bands —15— which are sufficiently flexible to enable them with the slats thereon to be unfolded to a substantially flat plane to enable the entire receptacle to be thoroughly cleansed inside and outside and stored in compact space

when desired or when removed from the bed —1—.

The ends of each band —15— are provided with clamping members —17— having their meeting ends provided respectively with overlapping apertured eyes —18— and —18'— for receiving a vertical key or locking rod —19— by which the ends of the bands —15— are locked to each other to hold the slats —7— in concentric relation to the axis of the vat or in concentric relation to the axis of the receptacle when the latter is placed upon the bed —1— ready for use.

15 The upper ends of the opposite arms —9'— of each of the frames —9— are preferably parallel for receiving and supporting the adjacent ends of the cross beam —10— which latter extends diametrically across the upper end of the receptacle —7— some distance above the same and is provided near its opposite ends with grooves —20— for receiving the upper parallel portions of the arms —9'— which are tightly pressed into the grooves —20— to hold the cross beam —10— in operative position.

That is, the arms —9'— of the frames —9— are normally tensioned to spring outwardly away from each other when disengaged from their respective trunnions —8'—, but when engaged with said trunnions the pressure incidental to springing the arms toward each other tends to hold the beam —10— against downward movement.

35 The means for pressing the materials as —a— within the receptacle —7— for expressing the liquid or juices from said material preferably comprises a circular press head or follower —22— and a conventional screw jack —23—, the press head —22— being of slightly less diameter than the interior of the receptacle —7— so as to pass freely into said receptacle from the top downwardly.

45 When the receptacle —7— is filled with the material to be pressed the follower —22— is placed on the upper surface thereof after which the jack —23— is placed upon the follower with its upper end directly beneath the lower face of the cross beam —10— whereupon the screw of the jack —23— may be turned by means of a handle —24— to bring the head of the jack against the underside of the cross beam —10— and then as the turning of the screw of the jack is continued by means of the handle —24—, the lower portion of the jack and follower —22— engaged thereby will be forced downwardly onto the material to press the same within the receptacle —7— for expressing the liquid therefrom.

The juices or other liquid thus expressed will pass outwardly through the spaces between the slats —7— or downwardly upon the upper surface of the bed —1— to enter

the trough —2— and thence to pass out through the outlet —3— into an underlying receptacle, not shown, this pressing operation being continued until the juices are entirely expelled from the material. 70

Operation

When the various parts of the apparatus are assembled in the manner described, the material from which the juices or liquids are to be expressed are placed within the receptacle —7— to rest upon the upper face of the central depressed portion of the bed —1— at the inside of the groove —2— after which the press head or follower —22— is placed upon the upper surface of the material, followed by the placing of the screw jack —23— upon the press head with its upper end directly under the central portion of the cross beam —10—. 80

The screw of the jack —23— may then be turned in the proper direction to engage its upper end with the underside of the cross beam, thereby forcing the press head —22— downwardly into the receptacle for compressing the material and expelling the liquid therefrom, said liquid collecting in the trough —2— from which it is conducted by gravity to the outlet —3— and into an underlying receptacle, not shown. 85

When the press is not in use the jack —23— and press head —22— may be removed and set aside after which the locking bolt or key —19— may be withdrawn upwardly from the bands —15—, thus permitting the bands with the slats thereon to be opened and removed from the top of the bed —1— whereupon the material which has been previously compressed may readily be removed from the bed and conveyed to any repository. 100

When the receptacle —7— is removed from the bed it may be unfolded to a substantially flat position to enable all parts thereof to be thoroughly cleansed after which it may be placed flatwise in compact space in any convenient place of storage. 110

The clamping plates —13— may then be withdrawn from the outer ends of the bolts —12— by simply loosening the nuts —14— and thus permitting the lower ends of the frames —9— to be withdrawn from their respective trunnions —8'—. 115

The opposite arms —9'— of the frames —9— may then be spread apart to release the cross beam —10— therefrom, thus permitting the frames and cross beam to be placed flatwise one upon the other in relatively small compact space. 120

The legs —5— may then be unscrewed from the respective sockets —6— and also stored side by side in compact space. 125

It is now evident that when all of the parts or units are dis-assembled they may be placed within a relatively small com- 130

pact space for storage, it being understood that prior to such storage the bed —1— and other parts of the apparatus will be thoroughly cleansed ready for reuse when needed.

When assembling the parts of the apparatus, the legs —5— will first be screwed into their respective sockets —6— whereupon the bed may be supported upon a 10 floor in a substantially horizontal position.

The receptacle —7— may then be folded to its cylindrical form and the ends of the bands —15— locked to each other by means of the pin or locking rod —19— after which 15 the receptacle may be placed in an upright position upon the upper surface of the bed at the inside of the groove 2.

The cross beam —10— may then be placed in operative position in the upper 20 ends of the frames —9— after which the latter may be mounted upon the trunnions —8'— and clamped in place by means of the plates —13— and nuts —14—, it being understood that when the frames are placed 25 upon the trunnions —8'— the opposite arms of each frame will be drawn toward each other to engage said trunnions, thereby compressing the upper ends of said arms firmly against opposite faces of the beam 30 —10— to hold the latter in operative position upon the frames.

The receptacle —7— may then be filled with the material to be pressed followed by the placing of the press-head —22— upon 35 the top of the material and then placing the screw jack —23— upon the press head with its upper end directly under the central portion of the cross beam —10— so that the turning of the screw in one direction 40 will force the press-head —22— downwardly into the receptacle —7— for compressing the material therein.

It will be observed that when the head of the jack screw —23— is unscrewed to engage the lower face of the beam —10— it 45 will have a tendency to turn said beam together with its supporting frames —9— in the same direction about the axis of the screw, and in order to avoid this, suitable stop shoulders —25— and —25'— are imbedded in the concrete base —1— to extend outwardly from opposite sides thereof across the front and rear edges of the front arms —9'— of the opposite frames —9— 50 directly above the clamping plates —13— and, therefore, some distance above the trunnions —8'— as shown in Figures 2 and 3.

If desired, a tubular metal socket —26— 60 may be imbedded in the concrete bed —1— between the outlet —23— of the trough

—2— and front portion of the receptacle —7— with its upper end open for receiving the handle —24— or locking pin —19— when not in use.

The construction and operation of the 70 machine is believed to have been fully shown and described, but obviously various changes may be made in the details thereof without departing from the spirit of the invention. 75

What I claim is:

1. A fruit press comprising a concrete base, trunnions imbedded in and projecting outwardly from the base, a receptacle resting on the base, upright frames mounted on the trunnions and extending upwardly therefrom some distance above the receptacle, a cross beam mounted on the frames across the top of the receptacle, a press head movable in the receptacle, a screw jack between the head and cross beam for forcing the head downwardly, bolts anchored in the bed, and clamping plates engaged with the outer faces of the frames and secured in place by said bolts for holding the frames against axial displacement from the trunnions. 80 85 90

2. In a fruit press of the character described, a concrete bed having trunnions imbedded therein and protruding from opposite sides thereof, a receptacle for the material to be pressed mounted on the upper face of the bed between said trunnions, upright frames mounted on the trunnions and extending upwardly therefrom above the receptacle, a cross beam mounted on the upper ends of the frames, means engaging the underside of the beam for compressing the material in the receptacle, and releasable means for holding the frames on the trunnions against axial displacement therefrom. 95 100 105

3. In a fruit press of the character described, a concrete bed having trunnions imbedded therein and protruding from opposite sides thereof, a receptacle for the material to be pressed mounted on the upper face of the bed between said trunnions, upright frames mounted on the trunnions and extended upwardly therefrom above the receptacle, a cross beam mounted on the upper ends of the frames, means engaging the underside of the beam for compressing the material in the receptacle, each of said frames being made in the form of an inverted U, the upper ends of opposite arms of said frames being engaged in grooves in the beam, said beam being engaged with the underside of the upper closed ends of the frames. 110 115 120 125

JAMES N. VILLANO. 125
